UNITED STATES PATENT OFFICE.

LEONARD V. HOSFORD AND DAVID DAVISON, OF PORTLAND, OREGON, ASSIGNEES, BY
MESNE ASSIGNMENTS, TO HOSFORD MOTOR CONSTRUCTION CO., A CORPORATION
OF OREGON.

TWO-CYCLE INTERNAL-COMBUSTION ENGINE.

Application filed December 19, 1924. Serial No. 757,064.

Our present invention is a modification of that disclosed in our co-pending application filed September 30, 1924, Serial No. 740,848 and it particularly has for its object to provide a modified construction of the cylinder head, to reduce the number of valves carried thereby, and to make it possible for the utilization in the cylinder head of but a single valve for air scavenging, air starting and compression release purposes.

In carrying out our present invention we provide a supplemental piston valve mechanism cooperatively connected with the source of the compressed air supply (used for starting purposes) and with the by-pass duct of the engine and so co-ordinate it with the operative mechanism for the fuel and scavenging valves in the cylinder head as to enable the several mechanisms to perform their functions at proper and desired times.

In its more specific nature the invention resides in those novel structures, combinations and arrangements of parts, all of which will be first fully described, and then be specifically pointed out in the appended claims, reference being had to the accompanying drawings, in which:—

Figure 1 is a plan view of a single engine unit employing the invention.

Figure 2 is a vertical section on the line 2—2 of Figure 1.

Figure 3 is a vertical section on the line 3—3 of Figure 1.

Figure 4 is an end elevation of the same.

Figures 5, 6 and 7 are diagrammatic views of the supplemental piston valve.

Figure 8 is an inverted plan of the cylinder head.

Figure 9 is a horizontal section thereof on the line 9—9 of Figure 2.

Figures 10 and 11 are detail views of the slip clutch hereinafter referred to.

Figure 12 is a front elevation, parts being in section, of the invention.

Referring now to the accompanying drawings, in which like numerals of reference indicate like parts in all the figures, 1 represents the bed which also constitutes the lower part of the crank case, 2 the upper part of the crank case, 3 the working cylinder, 4 the cylinder head, 5 the water cooling exhaust duct, 6 the reciprocating piston, 7 the stationary piston, 8 the connecting rod, 9 the wrist pin and 10 the crank shaft; the

general construction of all of which parts, 55 except the cylinder head, may be substantially that of our co-pending application above referred to.

The cylinder head is provided with a long narrow compression chamber 11 into one end 60 of which and in the direction of the length of the chamber and in a horizontal direction the fuel inlet valve is designed at proper times to inject a charge of fuel oil in an atomized state through the fuel inlet valve 65 port 12. 13 represents the governor which controls the operation of the engine, and as the construction of this governor may be of any approved type, such for instance as described in our co-pending application aforesaid, a detail description and illustration thereof is thought to be unnecessary, since no claim to the governor per se is made in this application.

The reciprocating piston is provided with 75 a concavo-convex head 14 and the working cylinder 3 is secured to the crank case 2 by bolts 15, while the stationary piston is secured to the working cylinder by similar bolts 15.

The cylinder 3 is provided with vertical recesses 16 for the wrist pin bosses to ride in. 17 is the by-pass inlet port, 18 the by-pass duct of the cylinder, 19 the by-pass duct of the cylinder head which delivers into the 85 scavenging air valve chamber 20 of the cylinder head and from which the air is in turn delivered into the working chamber. 21 is the valve seat for the scavenging valve and 22 the exhaust ports leading to the water 90 cooled exhaust duct.

The cylinder 3 is recessed at 23 for the flange 24 of the stationary piston 7 so as to insure proper alignment of these parts. 25 designates the slots in the stationary piston 95 through which the wrist pin bosses 30 project. The stationary piston is provided with air ports 26 of grid construction in its head which are controlled by a grid valve 27, the latter having ports 28 and being 100 mounted on a stud or bolt 29.

31 is the water jacket space of the cylinder head in which cooling water is circulated for the usual purposes and in the usual manner. 32 designates the combined scavenging 105 and air-starter valve which has a guide 33 and is held seated by a return spring 34. It is opened by a rocker arm 35 mounted on a

suitable bearing support 36 and itself operated in the manner presently explained.

- 37 is the fuel valve casing, 38 the fuel valve stem which is adapted to be engaged by the rocker arm 39 mounted on a bearing 40 and operated by a pull rod 41 that is in turn actuated by a camming lever 42, the roller 43 of which is adapted to cooperate with the cam 45 on the counterweight 44.
- 10 46 is a control shaft which has an eccentric stub 48 on which the governor actuated lever 47 having an eccentric bearing 47 is mounted. 49 is a lever and quadrant for effecting the changes in position of the shaft 46.
- 15 50 represents the slip clutch on the control shaft 46 for manipulating the scavenging air valve at times. A camming lever 51 operates the fuel pump 54 and the scavenging valve through the action of a cam 52 on 20 one of the counterweights of the crank shaft, the camming lever 51 being mounted on a bearing 53 on the shaft 46.

The fuel pump 54 includes a governor operated controlling lever 55 which is connected by connections 56 to the governor lever 57, the latter operating both the fuel pump governor-operated lever and the governor actuated lever 47. 58 is a governor action-regulating lever for causing the tension of 30 the governor spring to be increased or diminished and the action of the governor thereby varied to suit the requirements desired.

- 59 is a piston valve casing and support 35 which has a compressed air inlet port 60 and a port 62 which connects with a duct 61 from the by-pass duct 18. 63 is a piston operating within the casing 59 and having an open ended chamber 64. The piston also 40 has a lower port 65 for registering with the port 62 at times. 66 is the upper piston chamber which has an inlet port 67 and an outlet port 68. A return spring 69 tends to hold the piston against the action of the 45 camming lever.

70 is the piston rod which connects the piston with the camming lever 71 that is mounted by an eccentric bearing 72 on an eccentric 73 on the control shaft 46.

- 50 74 is a duplex roller-carrying lever to operate with the separate cam elements on the counterweight on the crank shaft. These elements are designated as follows: one cam having a high part 75 and a low part 77 and 55 the other having a high part 76 and a low part 78.

79 is the reversing shaft which is connected by a link 80 to the lever 74 so that by shifting the shaft 79 one or another of the 60 rollers of the duplex roller-carrying lever 74 may be brought into relation with its particular cam so as properly to time the action according as the engine is to run in one direction or another.

66 The construction and operation of the

fuel pump mechanism in the present instance may be that disclosed in our co-pending application above referred to and as its specific construction per se forms no part of the present invention detailed illustration and description of which is thought to be unnecessary.

So far as described the manner in which the engine operates as explained is as follows:—

With the engine at rest and it is desired to start it up under the action of the compressed air which is stored in any suitable reservoir (not shown) and conveyed by a suitable duct (not shown) to the port 60 of the piston valve mechanism, the attendant manipulates the control shaft 46 in such way that the cams will raise the camming lever that operates the fuel valve out of the range of influence of its cam so as to render the fuel valve inactive for the time being. The same operation of the control shaft causes the camming lever of the fuel pump and scavenging valve to move the scavenging valve to the open or unseated position. The same movement of the control shaft and lever brings one or the other of the cam engaging rollers of the duplex carrying lever 74 into the path of action of its particular cam on the balance weight of the fly wheel. During the period of air starting the scavenging valve in the cylinder head remains open and the air for starting purposes is admitted through the duct 61 directly into the by-pass duct of the engine cylinder.

When the cam engaging roller of the lever 74 is in the highest position, i. e. in engagement with the highest cammed portion of the counterweight, the ports 60 and 62 will be in communication via the ports 67, chamber 60 and port 68 to permit compressed air to enter the by-pass duct, to flow through the cylinder head into the working chamber of the engine cylinder. At the time, of course, when the port 62 is uncovered the reciprocating piston will have reached the top of its stroke and begun its downward travel under the influence of the now admitted compressed air. When the cam has travelled through an arc of ninety degrees the roller will have dropped down onto the reduced portion 77 or 78 as the case may be, of that cam 75 or 76 as the case may be, and the ports 60 and 62 will have been closed off. At this time the parts which were formerly in the position shown in Figure 5 have moved to the position shown in Figure 6. When the reciprocating piston has changed its motion to the upward stroke the roller will have left the reduced portion 77 or 78 of the cam and the port 65 will have been brought into register with the port 62 which allows the air to escape from the working chamber through the cylinder head by-pass duct, the cylinder by-pass duct and the in-

ternal chamber 64 of the valve 63 to atmosphere, which prevents the piston on its up-stroke compressing the air within the working chamber.

- 5 As soon as the engine has developed sufficient momentum the attendant again shifts the shaft 46 to the normal running position, i. e., that position at which the rocker arm 71 will be lifted to the non-operative position 10 and the rocker arms for the scavenging and fuel valves will be restored to their operative positions, whereupon the operation of the engine results in the reciprocating piston drawing a charge of fresh air into it 15 through the grid valve of the stationary cylinder while compressing a previous charge of air in the working chamber, then as it starts down on its working stroke the fuel valve opens to inject a spray of fuel into the 20 cylinder head combustion chamber where it becomes instantly ignited by the temperature of the highly compressed air and impels the piston downwardly on its working stroke. The interval during which the fuel 25 valve is allowed to remain open is approximately thirty-six degrees, after which the remaining movement of the reciprocating piston is under the expansion of the burnt mixture. As the working piston moves 30 downwardly it compresses the fresh air within it until the port of the piston registers with the by-pass inlet port, whereupon the compressed fresh air is blown into the by-pass duct and when the scavenging valve 35 is open (and this occurs as soon as the piston uncovers the exhaust ports) the fresh air will be blown through the cylinder head into the working chamber and expel any burnt residue therein, such fresh air charge 40 then being compressed on the next compression stroke of the piston as before.

The fuel pump operation and its control and the governor operation and control of the fuel valve, etc. being the same as that 45 disclosed in our co-pending application aforesaid and per se forming in their specific structures no part of the present invention, a detailed description of their construction and operation in this application 50 is thought to be superfluous.

The slip clutch is so designed that the jaws of the clutch are permitted to slip through a distance of thirty degrees or more, thus accomplishing the unseating of the 55 scavenging valve during the starting operation as before referred to.

When the engine is running under power 60 impulses the piston valve 63 remains in the position indicated in Figure 6, thereby preventing the escape of scavenging air.

From the foregoing description, taken in connection with the accompanying drawings, it is thought the complete construction, operation and advantages of the invention will 65 be clear to those skilled in the art, and we

desire it understood that changes in the details of construction, the proportioning of parts and arrangement thereof may be made without departing from the spirit of the invention or the scope of the appended claims. 70

What we claim is:

1. In two cycle internal combustion engines having piston controlled exhaust and by-pass ports and ducts, a cylinder head having a centrally located air port with a 75 valve seat and having a compression space, a scavenging valve in said head to deliver air from the by-pass into the working chamber, means causing the working piston to draw a fresh air charge into itself on one 80 stroke and deliver it compressed to the by-pass duct on another stroke and again compressing the air in the working chamber, a fuel valve on the head for injecting fuel crosswise of the head into the compressed 85 air within the compression space of the engine, and an auxiliary valve connected with the by-pass duct for delivering compressed starting air at times.

2. In two cycle internal combustion engines having piston controlled exhaust and by-pass ports and ducts, a cylinder head, a scavenging valve in said head to deliver air from the by-pass into the working chamber, means causing the working piston to draw 90 a fresh air charge into itself on one stroke and deliver it compressed to the by-pass duct on another stroke and again compressing the air in the working chamber, a fuel valve on the head for injecting fuel into the compressed air within the compression space of the engine, and an auxiliary valve connected with the by-pass duct for delivering compressed starting air at times, means to operate 95 said fuel and scavenging valves and 100 said auxiliary valve, and means to render said fuel and scavenging valves non-operative while said auxiliary valve is operative and vice versa.

3. In two cycle internal combustion engines wherein is provided a cylinder and head having by-pass ducts and ports, said cylinder having an exhaust port, a working piston controlling said ports, a scavenging valve and a fuel injection valve; an auxiliary piston valve mechanism and mechanical means to operate the same, said auxiliary valve mechanism having an inlet port to receive compressed starting air and having a delivery port for delivering the same to 110 the by-pass duct, and having passages to atmosphere, a valve piston controlling said ports of the auxiliary valve mechanism for the purpose of alternately admitting compressed starting air into said by-pass duct 115 to 120 impel the working piston and exhausting air from the by-pass duct to relieve compression.

4. In internal combustion engines of the character stated, a cylinder head having a 125

long narrow compression space of shallow depth, means to inject fuel oil horizontally in one end of said space toward the other end, said compression space being centrally enlarged, said head having an air duct to the enlarged space which is controlled by a valve carried by the cylinder head for the purpose of admitting compressed air into the compression space from the top, substantially as shown and described.

5. In two cycle Diesel engines of the ported cylinder type, piston controlling means to scavenge the working chamber with air after each working stroke of the piston, said means including a scavenging valve and a duct leading thereto, means to inject a spray of fuel oil into the compression space of the engine after the scavenging air is compressed therein by the piston, and means associated with the aforesaid parts for operating the engine under compressed air for starting purposes.

6. In two cycle Diesel engines of the ported cylinder type, piston controlling means to scavenge the working chamber with air after each working stroke of the piston, said means including a scavenging valve and a duct leading thereto, means to inject a spray of fuel oil into the compression space of the engine after the scavenging air is compressed therein by the piston, and means associated with the aforesaid parts for operating the engine under compressed air for starting purposes, said last named means including an auxiliary control valve for admitting compressed air into said duct at intervals and exhausting air therefrom at atmosphere at other intervals for the purpose described.

7. In two cycle Diesel engines of the ported cylinder type, piston controlling means to scavenge the working chamber with air after each working stroke of the piston, said means including a scavenging valve and a duct leading thereto, means to inject a spray of fuel oil into the compression space of the engine after the scavenging air is compressed therein by the piston, and means associated with the aforesaid parts for operating the engine under compressed air for starting purposes, said last named means including an auxiliary control valve for ad-

mitting compressed air into said duct at intervals and exhausting air therefrom to atmosphere at other intervals, and manually controlled shifting means to render said auxiliary control valve operative and said fuel and scavenging valve non-operative and vice versa.

8. In two cycle internal combustion engines having piston controlled exhaust and by-pass ports and ducts, a cylinder head, a scavenging valve in said head to deliver air from the by-pass into the working chamber, means causing the working piston to draw a fresh air charge into itself on one stroke and deliver it compressed to the by-pass duct on another stroke and again compressing the air in the working chamber, a fuel valve on the head for injecting fuel into the compressed air within the compression space of the engine, and an auxiliary valve connected with the by-pass duct for delivering compressed starting air at times, means to operate said fuel and scavenging valves and said auxiliary valve, and means to render said fuel and scavenging valves non-operative while said auxiliary valve is operative and vice versa, said valve operating means including circular counterbalances on the crank shaft of the engine, cam elements on said counterbalances and rocker arms connected with said valves and associated with said cam elements.

9. In internal combustion engines having a cylinder with a working chamber, a cylinder head unit comprising a body having a transversely elongated narrow compression space extending across the width of the working chamber, said compression space being centrally enlarged, said head having a fresh air duct terminating in a port in the central enlargement of said compression space and provided with a valve seat, a valve associated with said seat and carried by the cylinder head body, said cylinder head body having a fuel port in its side wall at one end of said elongated compression space and a fuel injection valve carried by the head body to deliver the fuel into the compression space transversely.

LEONARD V. HOSFORD.
